UNITED STATES PATENT OFFICE.

JOHN DOUGHERTY, OF INDIANAPOLIS, INDIANA.

GREASE-CUP-CAP BALANCED LOCKING CONSTRUCTION.

Application filed January 11, 1924. Serial No. 685,593.

To all whom it may concern:

Be it known that I, JOHN DOUGHERTY, a citizen of the United States, and a resident of Indianapolis, county of Marion, and 5 State of Indiana, have invented a certain new and useful Grease-Cup-Cap Balanced Locking Construction; and I do hereby declare that the following is a full, clear, and exact description thereof, reference being 10 had to the accompanying drawings, in which like numerals refer to like parts.

This invention relates to a grease cup cap locking construction. Various attempts have been made heretofore to securely lock 15 grease cup caps when subjected to extreme vibration and cycloidal movement to prevent the loss thereof. These devices while better than none have uniformly failed to give complete satisfaction. One of the main 20 reasons for such failure is that a balanced locking arrangement is not provided, and, therefore, in the cycloidal movement, the cap cooperates with the locking construction, the latter forming an eccentric pivot and thus 25 the cap ultimately becomes unlocked and is lost.

The chief object of the invention, therefore, is to provide a balanced locking construction for a grease cup cap that under 30 the most severe cycloidal and vibratory movement, will stay locked.

Another object of the invention is to construct the locking construction, so that the cap may be manually removed when desired, 35 yet offer considerably less resistance to the securing movement. In other words, the cap is yieldingly locked against any threading movement, but is increasingly locked against cap removal movement.

40 The features of the invention, in addition to the means for accomplishing the foregoing objects, will be more specifically pointed out herein.

The full nature of the invention will be 45 understood from the accompanying drawings and the following description and claims:

In the drawings, Fig. 1 is a top plan view 50 of a portion of a connecting rod or driver of a locomotive provided with a grease cup construction and showing the cap therefor. Fig. 2 is a longitudinal sectional view taken on the line 2—2 of Fig. 1 and in the direction of the arrows. Fig. 3 is a bottom plan 55 view of the cap and is taken on the broken line 3—3 of Fig. 2.

In the drawings 10 indicates a connecting rod construction having a bearing surface 11 and a lubricating channel 12 communicating therewith. The channel 12 communicates with a well or grease cup reservoir 13 having a threaded mouth 14. The body 15 of the grease cup is herein shown provided with a pair of diametrically positioned openings 16 which are parallel to each other and the axis of the well 13, and, therefore, may be stated to be axially positioned with respect thereto, although not in alignment.

Herein each of the wells 16 is illustrated as formed by drilling, and, therefore, since 70 drills usually are provided with a conical point, the same includes a conical bottom 17. Slidably supported in the well 16 is a plunger, locking pawl or projection 18 having an enlarged flange 19 and a reduced stem 20, all 75 concentric with each other. The body 18 is provided with a conical point 21. A coiled spring 22 is receivable by the well or recess 16 and bears against the flange 19 and is retained in axial alignment and concentric 80 with the entire aforesaid construction by the spring retainer stem 20. The other end of the coiled spring 22 is positioned axially by reason of the conical bottom wall 17 of 85 said well. Thus, the plunger or pawl having the conical point 21 is normally projected outwardly from the well 16. Herein means is provided for retaining said plunger against complete outward projection, and, therefore, removal. Herein such a construction is shown as a bushing or collar 23 90 rigidly secured in the well and adapted to overlie the flange 19 by the deformed portion 24. Other means may be provided, if desired, which also come within the disclosure of a retaining member for said plunger or locking pawl and rigidly secured in 95 said well or by a portion adjacent thereto; provided, however, said securing means does not normally extend beyond the face of the 100 grease cup construction indicated by the line 3—3. Since the foregoing description adequately describes the other locking construction, no further description thereof need be given.

Reference will now be had to the cap which is illustrated in detail in Figs. 1, 2 and 3. Herein the cap is shown including a main body portion 25 having a tool-engageable portion 26 which is recessed at 27 to lighten the same. The body portion 25 has a peripheral flange 28 adapted to overlie the 110

face of the grease cup construction and also the wells 16 containing the plungers previously described. The cap 25 is also provided with a threaded extension 29 recessed at 30 5 to lighten the same. Said extension 29 is oppositely positioned from the tool-engageable portion 26. The foregoing nut construction is old in the art, and it is to be understood that the threaded exterior of the 10 extension 29 is adapted to engage the threaded interior 14 of the well 13 and thus close said well and retain the lubricant therein.

In actual practice the lubricant is supplied to the well and the lubricant used is 15 usually very stiff. After the locomotive has traveled some fifty miles, the engineer proceeds to again tighten the cap upon the seat, for the lubricant by this time has become warm and does not offer as much resistance to the final seating of the cap. Should the engineman fail to again tighten the cap at the desired time, the cap, due to the cycloidal movement and vibration, will gradually become unthreaded from the 20 25 grease cup and be lost along the right-of-way. If the engineer should tighten the cap, as aforesaid, then subsequent traveling will also tend to loosen the cap; and if an inspection subsequent thereto is not made, the cap may become unthreaded and likewise be lost along the right-of-way.

With the foregoing invention, therefore, the cap is retained in a threaded position and will not become unthreaded and lost, 30 35 even though the engineer fails to tighten the same after the lubricant has become heated following fifty miles of travel, or therabouts.

The cap, which is the detachable element, 40 and that which is lost and replaced is herein shown, provided with a plurality of diametrically positioned pairs of conical openings 31, which by reason of the jig for simultaneously drilling the same, are not positioned so 45 that their axes are parallel to the cap axis, but are slightly inclined thereto, although each of the conical recess axes is parallel to the others. Herein three pairs of diametrically positioned openings are illustrated, 50 and it is believed six will be sufficient, although the number may be increased or decreased as desired.

While the preferred arrangement is to provide the recesses in the cap and the locking plunger constructions in the grease cup, the same may be reversed without departing from the invention in any degree whatsoever.

While the invention has been described in 60 great detail in the foregoing specification, the same is to be considered illustrative and not restrictive in character, such as for example as has been previously pointed, and the many modifications of the invention 65 which will readily suggest themselves to

those skilled in the art, some of which have been enumerated hereinbefore, are all considered to be within the broad purview of the invention, reference being had to the appended claims.

The invention claimed is:

1. The combination of a grease cup member, a cap member therefor, said members having a threaded connection therebetween, a well in one of said members normally covered by the other of said members, the other member having a recess therein adapted to register said well, a bushing partially closing said well and rigidly secured therein, and a locking member seated in the well and retained therein by said bushing and extending therefrom for seating in said recess.

2. The combination of a grease cup member, a cap member therefor, said members having a threaded connection therebetween, a yieldingly mounted locking plunger carried by one member, and a complementary plunger receiving seat in the opposite member for receiving said plunger, one of said complementary locking elements being axially positioned and the other slightly angular thereto for yieldingly permitting threading movement in one direction but yieldingly opposing threading movement in the opposite direction to a greater degree than the first-mentioned threading movement.

3. A device of the character described in claim 2 characterized by the provision of a plurality of plungers and a plurality of seats, said plungers and said seats being arranged in balanced relation and about the cup and cap axes.

4. The combination of a grease cup member, a cap member therefor, said members having a threaded connection therebetween, a plurality of yieldingly mounted locking plungers carried by one member, and a plurality of complementary plungers receiving seats in the other member for receiving said plungers, said plungers and said seats being arranged in pairs and diametrically positioned in balanced relation about the cup and cap axis, one of said complementary locking elements being axially positioned and the other slightly angular thereto for yieldingly permitting threading movement in one direction but yieldingly opposing threading movement in the opposite direction to a greater degree than the first-mentioned threading movement.

5. The combination of a grease cup member, a cap member therefor, said members having a threaded connection therebetween, a plurality of yieldingly mounted locking plungers carried by one member, and a plurality of complementary plunger receiving seats in the other member for receiving said plungers, said plungers and said

seats being arranged in pairs and diametrically positioned and in balanced relation about the cup and cap axis, and additional plunger receiving seats similarly arranged, 5 one of said complementary locking elements being axially positioned and the other slightly angular thereto for yieldingly permitting threading movement in one direction but in the opposite direction to a greater degree than the first-mentioned threading 10 movement.

6. A device of the character described in claim 2 characterized by the provision of a plurality of plungers and a plurality of 15 seats, said plungers and seats being arranged in balanced relation and about the cup and cap axis, and further by the diametrical positioning of said plungers in pairs and by corresponding positioning of 20 said seats, and further by the provision of

recesses additional in number to the locking plungers.

7. The combination of a grease cup member, a cap member therefor, said members having a threaded connection therebetween, 25 a yieldingly mounted locking plunger having a conical point carried by one member, and a complementary conical plunger receiving seat in the opposite member for receiving said plunger, one of said complementary locking elements being axially positioned and the other slightly angular thereto for yieldingly permitting threading movement in one direction but yieldingly opposing threading movement in the opposite direction to a greater degree than the first-mentioned threading movement. 30

In witness whereof, I have hereunto affixed my signature.

JOHN DOUGHERTY.
